DUPLICATING RIBBON ATTACHMENT

Julius C. Hochman, New York, N. Y.

Application July 9, 1948, Serial No. 37,748

18 Claims. (Cl. 197—153)

1

This invention relates primarily to bookkeeping machines, more particularly to the instrumentalities thereof or associated therewith for producing simultaneously two or more separate inked copies.

It is a primary object of the invention to render serviceable any of the various conventional makes of bookkeeping machines without any alteration whatsoever in the construction thereof for simultaneously producing by the use thereof two or more non-smudging inked typewritten copies of documents such as journal sheets, ledger cards, bills or the like which are subjected to considerable handling during the normal course of business and which would smudge if made with conventional carbon paper.

Another object is to provide means for accomplishing the above result which may be set or arranged for use with as great or greater facility than carbon paper (that is extremely awkward to use especially when large sheets are required for relatively large ledger cards or journal sheets that may run from 17 inches in length to 30 inches in width), which is more economical than carbon paper, which requires less frequent handling for removing and replacing the duplicating element used according to this invention in place of carbon paper and wholly obviates the special precautions and operations required in effecting erasures in the course of typing where carbon paper is used.

Another object is to provide for accomplishing the above results, an auxiliary ribbon supporting attachment or accessory device of simple construction, which may be securely retained on the machine and which automatically exposes continually changing areas of ribbon to type impact and throughout the use thereof, automatically maintains the ribbon in sufficiently taut condition for best service.

Another object is to provide a ribbon holder of the above type from which the ribbon may be readily removed and upon which the ribbon may be rearranged for utilizing fresh areas thereof, or a new ribbon affixed by simple manipulation without danger of smudging the fingers.

Another object is to provide a ribbon frame of the above type, which may be formed substantially solely from metal stampings, which in use may be readily applied upon the machine, without resort to tools, or skilled or time consuming fastening manipulation and which may as readily be removed from the machine, which co-ordinates with the parts of the machine automatically to assure proper co-relation for effective use, which does not interfere with the normal operation of

2

the paper clamps, bail or other paper holding means or the line spacer, and which is free from interference with the primary ribbon mechanism.

Another object is to provide frames of the above type which readily admit of the use of more than one ribbon on a single ribbon carrying element or the use of more than one ribbon carrying element for the preparation simultaneously of more than one inked typewritten copy in addition to the single typewritten copy for which the bookkeeping machine is designed.

Another object is to provide a device of the above type for use with front feed type bookkeeping machines, that makes collated form insertion faster, neater and more accurate than when conventional carbon paper is used with such machine.

Another object is to provide a device of the above type that may be readily manipulated so as to fit between the component elements of a bookkeeping machine.

Another object is to provide a ribbon holder of the above type which in operative position will retain a ribbon thereon so as to afford substantially complete visibility of the paper immediately therebelow.

Another object is to provide a holder of the above type constructed and arranged to retain a ribbon thereon so that the type heads will strike near the top edge of said ribbon to afford complete visibility of the typed line upon rotation of the platen one space and also to provide complete utilization of said ribbon upon end to end reversal thereof on said holder.

35 A feature of the invention is the use of an open frame, carrying a length of ribbon and so constructed that when positioned upon the platen of a conventional bookkeeping machine and the machine is set for operation, the frame becomes 40 inherently coordinated therewith to imprint additional inked copies, the frame with its carried ribbon shifting longitudinally with the platen with each movement of the latter after each typing operation, to avoid exposure of the identical ribbon area to successive type impacts.

45 In a preferred construction, the frame is a substantially rigid generally U-shaped metal piece, to be laid upon the platen, with its cross bar extending longitudinally of the latter, an inked ribbon being releasably attached to said frame to bridge between the free ends of the arms thereof, which extend downward from the bar and are preferably curved to conform to the curvature of the platen.

50 Another feature is the provision of a plurality of superposed insertion guides affixed to one of

the arms of the frame and the mounting of a single ribbon on said arms so as to bridge therebetween, said guides facilitating the insertion of a pair of paper forms so as to straddle said ribbon.

Another feature is the provision of a plurality of superposed insertion guides affixed to one of the arms of the frame and the mounting of a pair of superposed ribbons on said arms so as to bridge therebetween, said guides facilitating the insertion of paper forms between said pair of superposed ribbons.

Another feature is the construction of the ribbon carrying arms of the frame in such manner as normally to urge the ribbon thereon away from the platen to the plane of form insertion or removal, in order to facilitate insertion and positioning of the forms in front of and behind the ribbon and in front of the platen of a front feed throat type machine exemplified by the well known National Cash Register Class 3000 bookkeeping machine and automatically to position said ribbon adjacent said platen when the front feed throat is closed.

In the accompanying drawings in which are shown one or more of various possible embodiments of the several features of the invention:

Fig. 1 is a fragmentary perspective view of the carriage of a front feed bookkeeping machine showing installed one embodiment of the attachment of the present invention,

Fig. 2 is a transverse cross sectional view taken along line 2—2 of Fig. 1 showing in full lines the forms in place thereon and in dot and dash lines the machine in form receiving position,

Fig. 3 is a fragmentary perspective view of the device indicating the manner of use of the form insertion guides,

still another embodiment, for use with machines in which the typing is performed from beneath the platen, and in which free access to the platen is obstructed by carriage elements,

Fig. 19 is a fragmentary transverse cross sectional view of the device shown in Fig. 18 mounted on a machine, and

Fig. 20 is a fragmentary perspective view of one of the ribbons.

Referring now to the drawings, Figs. 1, 2 and 3 indicate illustratively the carriage of a Remington front feed type bookkeeping machine showing the platen 31 with the operating knobs 32 thereof, the bail rod 33 with the paper rollers 34 thereon, the support arms 35 for the bail rod which also mount the bail rod brace 36 and the stiffener strut 37 therebetween. The machine also includes resilient deflector plate 38 and the movable deflector plate 39 which extend the length of the platen with the lower end 41 of the movable deflector plate 39 extending beyond the lower end 42 of the resilient deflector plate 38. In addition, the machine includes the fixed table 43 which also extends the length of the platen and has its lower end 44 underneath and guiding the lower end 41 of the movable deflector plate 39, which plate rests on fixed paper table 43 and slides forward and backwards on the lower end 44 thereof.

The machine is also equipped with front feed paper clamp rollers 46 only one of which is illustratively shown, and which may be moved away from the platen simultaneously with an upward and outward movement of movable deflector plate 39, by suitable mechanism (not shown) when it is desired to insert forms into the machine in the manner hereinafter described.

A line finding wire 47 is also provided, supported by means (not shown) at each end of the platen and positioned slightly above the upper edge of the type head 101 which strikes the primary ribbon 40 shown in Fig. 2 to make an impression on the top form in the machine.

All the foregoing construction is conventional and per se forms no part of this invention.

Proceeding now to the attachment device or holder of the present invention, which mounts ribbons 91 and 92, or a single ribbon if desired, the holder as illustratively shown in Figs. 4, 5 and 6 may comprise a spring metal angle bar 52 which may be of length nearly equal to that of the platen, having end arms 57 extending at right angles thereto, the arms 57 bent to conform to the curvature of the platen. Although arms 57 may be formed integrally with bar 52, desirably each of the arms 57 has a laterally extending member 55 conforming in shape to bar 52 and affixed thereto preferably by rivets 56.

The curved arms 57 are desirably provided, preferably at their inner edges, with integral upstanding ledges 58 which stiffen said arms, said ledges being notched as at 59 for the purpose to be set forth.

Special retainer means is preferably provided for releasably securing the ribbon ends to the arms 57 of the frame. In a preferred construction shown, the free end 61 of each of the arms 57 may be substantially rectangular in shape and has a lock shoulder 62 integral with the outer edge thereof.

Each of the ribbons 91 and 92, which are ink impregnated and with an impervious backing on one face, at each end desirably has a tab 63, preferably of impervious fabric affixed theron as shown in Fig. 20 and has parallel slits 64 and 65 therein through the tab and ribbon which extend parallel to the length of the ribbon, and may be

of equal length as shown in Fig. 6 to accommodate the end 61 of the arms 57. It is of course to be understood that the tabs 63 could be eliminated and the slits 64 and 65 through the ribbon alone could accommodate end 61 of arm 57.

The ribbon with its tabs 63 is a distinct article of manufacture, of length depending upon the distance between arms 57. In mounting the ribbon upon the frame, the application of the tabs over the ends 61 of arms 57 results in tension of the ribbon slightly to bow the resilient angle bar 52.

As the distance between the outer edges of the slits in the ribbon is shorter than the distance between the outer edges of the ribbon attaching ends 61 of the frame arms, the lock shoulder 62 on arms 57 respectively, will snap under the outer end of top slits 65 when the tabs are affixed on arms 57, securely yet releasably to retain the respective lock shoulders under the associated outer ends of slits 65, thereby securely retaining the ribbons on the arms yet permitting ready release thereof when desired.

A plurality of superposed spring sheet metal form guides are provided, three of which are illustratively shown, designated by the numerals 67, 68 and 69. Although such guides could be mounted on either or both ends of the frame, in the embodiment herein chosen to illustrate the invention, they are desirably affixed to arm 57 on the left side of the frame.

The front guide 67 and rear guide 69 each has but a single ply whereas the middle guide 68 is reversely bent to form a separable double ply with the folded end 71 at the top and the open portion 72 at the bottom. As is clearly shown in the drawings, the lower portions or guide tracks of the guides are desirably curved to conform substantially to the curvature of the platen, are in nested relation and desirably taper inwardly along their outer edges as at 74 with the end 75 of the front guide 67, preferably extending substantially beyond the two ends 76 and 77 of the middle guide 68, and the end 78 of the rear guide 69, which latter three ends are in stepped relation with the rearmost end 78 being shortest in length.

The upper portions of the guides are preferably substantially flat as shown, with the upper portion of the double ply middle guide 68 projecting forwardly from the upper portion of the rear guide 69, to form a space 81 therebetween and with the upper portion of the front guide 67 being substantially parallel to the upper portion of the middle guide 68 to form a space 82 therebetween, and the ends of the upper portions are preferably of graduated height as at 79, preferably increasing toward the rear, to further facilitate the insertion of forms between the guides.

In order securely to retain the guides in place, the rear guide 69, the bottom ply 84 of the middle guide 68 and the front guide 67 each desirably has a laterally projecting arm 86 integral therewith, which three arms 86 are secured to arm 57 as by a pair of rivets 87 securely to retain all three guides in superposed relation.

It is to be noticed that the ends 76, 77 and 78 of the guides 68 and 69 are substantially transversely aligned with the end 61 of arm 57 and the curved portion of front guide 67, which is designated by the numeral 73, is of greater width than the other guides so as to cover the latter, and also to cover all but the outer edge portion of arm end 61, with its lower end 75 extending substantially below the end of the frame arm 57. The ribbons 91 and 92 when mounted on the

frame are in superposed and aligned relation with their inked faces toward the rear. As shown in Figs. 4 and 5, the rear ribbon 91 is against the underface of the curved end of guide 69 and the front ribbon 92 is between the separable double plies or guide tracks of the middle guide 68.

As the ends of guides 67, 68 and 69 overlap as previously described, the stepped arrangement thereof facilitates the insertion of the ribbons therebetween.

By the construction above described when the frame is laid upon the platen of the bookkeeping machine, as the distance between the upstanding ledges 58 on the arms 57 is preferably somewhat less than the length of the paper bail 33 of the machine, the bail 33 may readily be positioned so as to register with and enter notches 59 in ledges 58 and thus retain the frame in position while still permitting limited longitudinal movement thereof with respect to the platen.

In insertion or open throat position of the Remington front feed bookkeeping machine illustratively shown in Figs. 2 and 3, with the bail in raised position, with its roller 34 out of contact with the platen and with the clamp roller 46 spaced from the platen 31 in the dot and dash position (shown in Fig. 2), the journal sheet J is inserted from the rear between the resilient deflector plate 38 and the platen 31 and is pushed directly about the latter until it passes up in front of the platen for a short distance. The ribbon carrying frame is then dropped loosely on the platen with its ribbons 91 and 92 on top of the journal sheet, and with the lower end 75 of the front insertion guide 67 inside of the movable deflector plate 39, which at this time is in its upper or form receiving position, as also best shown in Fig. 2. The top end of journal sheet J may pass above the horizontal angle bar 52 of the frame as shown, or underneath, if desired, and the bail is then lowered with the bail rod 33 resting freely in the notches 59 of the ledges 58, thus positioning the frame with the ribbons 91 and 92 located along the writing line of the machine, and with the bail rollers 34 pressing the journal sheet J against the platen as clearly shown in Fig. 2.

In one of the many widely used bookkeeping operations, the user then takes a ledger form L with a statement form S on top thereof and preferably held in proper collated position with respect thereto for an entry at the desired places on each form and positions the corner 95 of the ledger form L between the upper portions of guides 69 and 68 and the corner 96 of the statement form S between the upper portions of guides 68 and 67 as is shown in Fig. 3 and thereupon pushes the ledger and statement forms downward and around the platen until the proper writing line is brought into position as indicated by the line finding wire 47.

It is to be noted that as the portions of the ribbons 91 and 92 beneath the guides are not in contact, as the ends 76, 77 of guide 68 straddle ribbon 92 and the end 77 of guide 68 and the end 78 of guide 69 are in front of ribbon 91, and as the corners 95 and 96 of the respective forms L and S, are between the smooth faces of the opposed guides, the forms will not catch on the top edges of the ribbons and hence there will be nothing to impede their movement down and around the platen. Thus the forms may readily be properly positioned in the machine with ribbon 91 between the face of the journal sheet J and the back of the ledger form L and ribbon

92 between the face of the ledger form L and the back of the statement form S. The user then need merely slide the forms S and L longitudinally of the platen to clear the guides until they are in proper columnar position with respect to the journal sheet.

In the open position to permit removal of or to receive the ledger and statement forms L and S, the movable deflector plate 39 is spaced from the platen 31, as are the clamp rollers 46 and line finding wire 47, all of which is clearly shown in dot and dash lines in Fig. 2. It is to be noted that when the deflector plate 39 is moved to open position from its closed position shown in full lines in Fig. 2, it will ride on the outer surface of end 75 of guide 67. This will prevent the deflector plate 39 from catching on the bottom end of arm 57 or on the bottom edges of the ribbons. If desired, a piece similar to end 75 could be provided on the other end of the frame for the same purpose. When the forms L and S and journal J are correctly correlated, the deflector plate 39, the clamp rollers 46 and line finding wire 47 are moved against the platen 31 as shown in full lines in Fig. 2 securely holding the ledger and statement forms in place with the line finding wire aligned with the top edges 98 of the superposed ribbons 91 and 92, and with the bottom edge of the last previously typed entry on the forms.

With the machine in its closed position, the deflector plate 39 presses against the extending lower surface 75 of top guide 67, thus retaining all of the flexible guide leaves in close proximity with the platen, so that in the lateral movements of the machine carriage, no possibility exists of any elements mounted on the moving carriage colliding with forwardly projecting stationary elements, such as the type guides, ribbon vibrator, etc. that are mounted on the machine base.

In use, the type impact of typehead 101 through the primary ribbon 46 will imprint the statement form as usual and through ribbons 92 and 91 will cause a similar ink imprint upon the ledger form L and journal form J.

The successive movements of the carriage platen after each depression of the type keys will carry the ribbon frame lengthwise with the platen and hence expose a fresh area of the ribbons to the type heads, which only move transversely of the platen always to strike at the same position relative to the frame of the machine, hence substantially the entire length of the ribbon at the top half thereof will be utilized.

As the line finding wire 47 is aligned with the upper edge 98 of the ribbons it is apparent that the type heads will strike the latter close to such upper edge and hence it is merely necessary to rotate the platen one line space to see the line just typed, which greatly facilitates entry of figures on the forms. Because of its symmetrical construction, when the ink in the half of the ribbon being utilized is exhausted, the latter may be reversed end to end so that the unused lower half thereof is brought into type impact position adjacent the line finding wire and in this way substantially the entire serviceable area of the ribbon is effectively used.

By the use of the above described frame with its insertion guides, form insertion in front feed type machines is greatly facilitated. Statement and ledger forms or forms of similar nature may be rapidly collated without the necessity of handling additional loose carbons, and the guides direct the forms automatically into proper posi-

tion between the ribbons. Every typed item on the journal sheet is fully visible, for unimpeded reference thereto, as is desired in many book-keeping operations.

Although the device shown in Figs. 1 to 6 utilizes but two ribbons, it is of course to be understood that a single ribbon or a greater number of ribbons could be utilized and an additional double ply guide provided for each additional ribbon.

Due to the loose mount of the ribbon carrying frame on the platen, the frame is free to move horizontally along the platen, in response to such forces as those of momentum and inertia, generated during normal carriage movement and carriage tabulation. Preferably this movement of the frame along the platen is limited to a distance equal to approximately one type space, the movement being preferably controlled by spaced collars (not shown) mounted on bail rod 33, for abutment by the upstanding ledges 58 on the frame arms 57. A somewhat lesser amount of vertical movement of the ribbon, with respect to the line of type impact, is also provided for, by making notches 59, into which the bail rod 33 rests, slightly wider than the diameter of the bail rod. It should be noted that where visibility of the last typed item on the journal sheet J is desired, the extent of such vertical movement of the ribbon may preferably be less than where such visibility is not required.

It is obvious that the various movements of the ribbon carrying frame with respect to the point of type impact, as outlined above, result in a complete utilization of the ribbon area adjacent the writing line of the machine, and that the provision of a symmetrical ribbon capable of end to end reversal with two such copy making areas, makes possible an extremely large amount of typing before ribbon changing becomes necessary.

Where a bookkeeping machine, illustratively a front feed throat type machine such as that sold by the National Cash Register Company, of the type shown in Fig. 8 is used, having a platen 104, a bail rod 121 extending longitudinally thereof and a supporting rod 118 also extending longitudinally thereof, the device shown in Figs. 1 to 6 has been modified to adapt it for use with such machine so that a simple operation, such as making entries on a bill and journal, may be performed with great facility.

As shown in Figs. 7 and 8, the ribbon frame comprises a spring metal angle bar 103 of length nearly equal to that of the platen 104, preferably having substantially L-shaped members 105, each with an arm portion 106 substantially conforming in shape to angle bar 103, affixed to the ends thereof as by rivets 106. Preferably integral with arm 107 at the upper edge thereof adjacent the end of bar 103 and extending parallel to the horizontal portion 108 of said bar, is a hanger 109, and on the outside of said hanger 109 and spaced slightly therefrom is a spring clip member 111 which comprises a curved resilient strip extending substantially parallel to horizontal portion 108 and having an upturned end 112, the function of which clip will be hereinafter described.

Extending at right angles to arm 106, is end arm 113, the major portion 114 of which may be curved to generally conform to the curvature of the platen. The curved portion 114 may be provided preferably at its inner edge, with an up-

standing stop 115 which serves to aid in retaining the frame in place when it is mounted on the machine in the manner hereinafter set forth. The end of portion 114 is desirably reduced in width, is preferably substantially rectangular in shape as at 116 and has a ribbon retaining or lock shoulder 117 integral with the outer edge thereof.

In use of the device, a ribbon 100 is positioned on the ends 116 of arms 113 in the same manner as previously described with respect to Figs. 1 to 10. The frame above described may be attached to the machine by positioning the hangers 109 so that they straddle rod 118 as shown in Fig. 8, in which position the resilient clips 111 will encircle said rod 118. The frame will thereupon pivot around rod 118 to bring the ribbon carrying arms 113 in contact with the platen with the ribbon along the writing line. The bail rod 121 mounted on pivoted member 122 is then positioned so that it comes to rest above the upper portion of arms 113 with stops 115 thereagainst. Thus the frame will be loosely, yet securely retained against the platen.

Where a wide form and a long platen is used which requires a long frame and a long ribbon, the latter may bow when the platen is rotated due to the frictional dragging of the forms and hence may be drawn away from the writing line.

In order to prevent bowing of such ribbon, a support bracket 123 may be provided which is shown in Fig. 9. The bracket which is preferably a strip of resilient sheet metal is preferably formed with a substantially L-shaped upper portion 124, the vertical leg 125 of which has a laterally extending flange 126 which extends over and grips the upper edge of the vertical portion 127 of the angle bar 103. The horizontal leg 128 of bracket 123 may have two inturned ears 129 which extend over the horizontal portion 108 of the bar 103, securely yet slidably to mount the bracket thereon. The lower portion of the bracket is curved to conform to the curvature of the platen and desirably has a vertical slot 130 in the end thereof through which the ribbon 100 is passed. As the length of the slot is substantially equal to the width of the ribbon, the bracket will provide a support for the tensed ribbon intermediate the ends thereof.

It is of course to be understood that where said support bracket is used, it would be positioned along the horizontal angle bar of the frame at a point where no entries will be made on the forms and hence the type heads will not strike against the bracket.

In Figs. 10 to 14 inclusive, the device shown in Figs. 7 and 8 has been modified so that it may be used on the National Cash Register machine above mentioned to make entries, as for example on a statement sheet, a ledger sheet and a journal sheet.

Associated with the platen 104 is a front plate 136, usually of Lucite or other transparent plastic having a paper table 138 associated therewith, said paper table 138, said platen 104 and said plate 136 being movable from the closed operating position of the machine shown in Fig. 10 to the open or form insertion position shown in Fig. 11.

The ribbon frame which may be similar to the one shown in Figs. 7 and 8, as best shown in Fig. 12 has affixed to each of its end arms 113, or formed integrally therewith if desired, and extending longitudinally thereof an extension arm 141 which may be curved generally to conform to the curvature of the platen. At the end of arm extensions 141 on each side thereof desirably is

an upstanding ear 142 and 143 respectively, each having an opening therethrough.

5 A ribbon holder 145 is provided, having laterally projecting studs 146 on the base 147 thereof preferably integral therewith, which fit into the openings in ears 142 and 143, whereby said ribbon holder may be pivotally mounted on said extension arm 141. The pivotal axis of ribbon holder 145 is preferably inclined inwardly, which may readily be accomplished in any of a plurality of ways and preferably by making the opening in outer ear 142 further from the surface of extension arm 141 than the opening in the inner ear 143. The free end of ribbon holder 145 substantially conforms in configuration to the end 116 of arm 113 which has already been described with respect to the embodiment shown in Figs. 7 and 8 and hence need not be further described. Ribbon holder 145 has an upwardly extending closing lever 152 which may comprise a strip of spring steel with the free end 153 thereof slightly curved as shown. Although lever 152 may be integral with ribbon holder 145 it desirably is affixed thereto on the front face thereof preferably by rivets 151.

20 In use of the device, ribbons 156 and 155 are positioned on the ends 116 of arms 113 and on the ends of ribbon holders 145 respectively in the same manner as previously described with respect to Figs. 1 to 6.

25 When the frame above described, is hung from rod 118 with the spring clip portion 111 and hanger 109 straddling rod 118 as shown in Figs. 10 and 11, the frame will pivot around rod 118 to bring the ribbon carrying arms 141 in contact with the platen with the ribbon along the writing line. The bail rod 121 is then positioned so that it comes to rest above the upper portion of arms 113 against stop 115. Thus the frame will be 30 securely retained on the machine to move lengthwise thereof with the platen, but capable of independent free shift of itself as previously described with reference to the device shown in Figs. 1 to 6.

35 40 45 With the machine in open throat position as shown in Fig. 11, and the transparent plate 136 pivoted away from the platen 104 the ribbon holders 145 by virtue of the inward inclination of their pivotal axes, will have automatically pivoted outwardly away from extension arm 142 by reason of the force exerted by the bowed resilient frame and its arms reacting against the resistance of the tensed ribbons on such ribbon holders. As lever 152 is pressed against plate 136, 50 it will follow the latter under the urging of ribbon holders 145, and thus it is not necessary manually to move the ribbon 155 away from the platen.

55 As ribbon 156 on arms 113 remain in juxtaposition to the platen 131 against the journal sheet J thereon and as ribbon 155 will be spaced from the platen and from the Lucite front plate 136 as is shown in Fig. 11, it is a relatively simple matter to position a statement and a ledger form which if desired may be previously collated, so that the latter is between ribbons 155 and 156 and the former is between plate 136 and ribbon 155.

60 65 70 When the machine is to be operated, as the plate 136 is moved from the position shown in Fig. 11 to that shown in Fig. 10, it will push lever 152 and pivot the ribbon holders 145 to operative position so that ribbon 155 will be moved parallel and in close proximity to ribbon 156. When the type head (not shown) strikes against the

primary ribbon (not shown) it will imprint the statement form as usual and through ribbons 155 and 156 cause a similar ink imprint to be made on the ledger form and the journal sheet.

The successive movements of the platen after each depression of the type key will cause the ribbon frame to move both with the platen, and independently on the platen, and hence expose fresh areas of the ribbon to the type heads.

A modification of the device shown in Figs. 10 to 14 inclusive, is shown in Fig. 15 in which corresponding parts have the same reference numerals primed. An arm 165, of spring steel, is superposed on and affixed as by riveting as at 166 to the upper end of arm 113' or it may be formed integrally therewith. The lower portion 167 of arm 165 is curved to conform to the curvature of the arm 113', overlaps the end of said arm and is reversely bent as at 168 forming a resilient portion thereat, the reversely bent portion 169 diverging outwardly as shown in Fig. 15 and having the ribbon holding conformation thereon heretofore described with respect to the embodiments shown in Figs. 1 to 14. A closing lever 152' similar to the one shown in Figs. 10 to 13 is affixed to the reversely bent portion 169 by rivets 151'.

As the operation of the device shown in Fig. 15 is the same as that shown in Figs. 10 to 14, it need not be further described.

In the embodiments shown in Figs. 10 to 15 but one ribbon is carried by ribbon holders 145 and 169 respectively. However if it is desired to mount two or more ribbons thereon, the insertion guides shown in Figs. 1 to 6 could be incorporated on ribbon holders 145 and 169 respectively. As the construction and operation of such combined structure is readily apparent in view of the foregoing description, it need not be further described.

The embodiment of the ribbon holding arm shown in Figs. 16 and 17 is for use with a book-keeping machine having a pivoted indicating plate 171 in front of the platen 172, where it is desired to utilize a writing line substantially the entire length of the platen.

To this end, curved arm 173 which is affixed to the cross bar of the frame (not shown) at right angles thereto, has a laterally extending wing 174 depending therefrom which forms an obtuse angle 178 with respect to arm 173, the ribbon holding end 176 of said wing having the same configuration as the ribbon holding arms previously described.

To use this device, the ends of the platen are reduced, preferably by beveling as at 179 beyond the maximum paper width possible for use, to accommodate wing 174 as is shown in Fig. 17. Thus the ribbon holding end 176 will not abut against the obstructing head 181 of the pivot pin for the plate 171 and a writing line of substantially the entire useful length of the platen will be available for use.

The embodiment shown in Figs. 18 and 19 is especially for use with a machine in which free access to the platen is prevented by obstructing rods as in the Burroughs bookkeeping machine which has a platen 184, a pair of rods 185 and 185' longitudinally thereof and a third rod 187 extending longitudinally thereof. With the platen so surrounded by obstructing rods, it is extremely difficult to insert a ribbon frame with rigid arms so curved as to fit the platen, for during such frame insertion, it is necessary for the curved arms and the ribbon 188 to pass be-

tween rods 185 and 187 and the platen and lie flush with the underside of the platen as is shown in solid lines in Fig. 19.

To this end, the ribbon frame comprises a spring metal angle bar 191 of length nearly equal to that of the platen 184 and substantially L-shaped members 195 of spring steel having an arm portion 196 substantially conforming in shape to angle bar 191 and affixed thereto as by rivets 197. Preferably integral with arm portion 196 and extending rearwardly therefrom as shown in Figs. 18 and 19 is attachment arm 198, the free end of which is reversely bent as at 199. Arm 198 has a longitudinal slit 201 therein which extends through the reversely bent portion 199 and which form a projecting hanger 202 and a spring clip 203, the end 204 of the latter being curved slightly as shown. Integral with arm 196 and extending at right angles thereto is end arm 205, the major portion 206 of which is curved to conform to the curvature of the platen 184 and which is provided, preferably at its inner edge with an upstanding stop 207. Although members 195 and angle bar 191 are shown as separate members, it is of course to be understood that they could be formed from but a single piece.

At the end of curved portion 206 of arm 205 on opposite sides thereof are upstanding ears 208 and 209 respectively, each having an opening therethrough. A ribbon holder 211 is provided having integral pivots 214 at the base thereof, the ends of the pivots extending respectively through the openings in ears 208 and 209 securely yet pivotally to retain the ribbon holder 211 on arm 205.

The free end 216 of ribbon holder 211 is substantially the same as the end 116 of arm 113 shown in Fig. 7 which has been previously described in detail and hence need not be further described.

In the use of the device shown in Figs. 18 and 19, ribbon 188 is positioned on the ends 216 of ribbon holder 211 in the manner previously described. To mount the frame above described, on the machine, it is necessary for the ribbon 188 to pass between bar 187 and the platen 184. This would be extremely difficult if not impossible to accomplish, were the ribbon holder 211 integral with the arms 205 or permanently affixed in the position shown in full lines, by reason of the limited space available for manipulation; and the obstructing presence of the pair of rigid bars 185, 185'.

However by reason of the pivotal connection of the ribbon holder 211 to arm 205, the ribbon holder can be pivoted to the position shown in dot and dash lines in Fig. 19 in which it lies in substantially the same plane as arm 205. It is thereupon a relatively simple matter to pass the ribbon 188 between rod 187 and platen 184 at which time the ribbon holders 211 are pivoted so that ribbon 188 therebetween is moved against the platen from the position shown in dot and dash lines in Fig. 19 to the position shown in full lines.

With the spring clip portion 203 and protruding hanger 202 of attachment arm 198 around bar 185 and with stop 207 against bar 187, the frame 186 will be securely retained in position on the machine, held against pivotal movement about bar 185 but movable longitudinally with the platen, which is free to rotate, and movable independently thereon as previously described.

By the use of the devices hereinabove described,

it is apparent that duplicate inked copies may be made on a bookkeeping machine without the need for carbon paper which is relatively expensive, slow and difficult to handle and smudges the hands of the user and the forms being typed, and loses its legibility by further smudging with each handling of the finished form.

The ribbons herein utilized, enable erasures to be made by simply rotating the platen so that the erroneous entry is no longer aligned with the ribbon. As there is no duplicating medium such as carbon paper beneath the erroneously typed character, it can be erased without the precautions taken when carbon paper is used. Thus the speed of correcting is considerably enhanced.

The term "bookkeeping" as herein used, is not limited to machines that record as such numerical accounting entries, but embraces within its scope other machines in which the attachment herein disclosed has utility, among which are punched card controlled tabulators, typewriters and computers.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention what I claim as new and desire to secure by Letters Patent of the United States is:

1. In a machine of the front feed type including a platen and means movable with respect to such platen from typing position to form inserting position; the combination therewith of a frame, means on said frame coacting with said machine to position said frame on said platen, ribbon mounting means near opposite ends of said frame, removably to retain the respective ends of a plurality of ribbons to extend therebetween longitudinally of said frame, and insertion guide means associated with said frame to facilitate the simultaneous insertion of a plurality of forms in correct relation with respect to such ribbons.

2. In a bookkeeping machine of the type including a platen; the combination therewith of a ribbon carrier comprising a frame resting upon the platen and movable longitudinally therewith, means on said frame coacting with such machine to position said frame in place on said platen, ribbon holding means on said frame at each end thereof, said frame having a plurality of superposed ribbons mounted on said ribbon holding means and extending in front of said platen longitudinally thereof, and insertion guides mounted on said frame and associated with said ribbons, whereby an entry form may readily be inserted between adjacent ribbons.

3. In a bookkeeping machine of the type including a platen; the combination therewith of a ribbon carrier comprising a frame resting upon the platen and movable longitudinally therewith, means on said frame coacting with such machine to position said frame in place on said platen, ribbon holding means on said frame at each end thereof, said frame having a plurality of superposed ribbons mounted on said ribbon holding means and extending in front of said platen longitudinally thereof, and a pair of superposed insertion guide members mounted on said frame between adjacent ribbons whereby an entry form may readily be inserted between said pair of guide members and thereupon moved to clear said guide

members and be positioned between said adjacent ribbons without abutting against the upper edges of said ribbons.

4. In a bookkeeping machine of the front feed type including a platen, and a movable deflector plate in front of said platen, longitudinally thereof and extending thereunder; the combination therewith of a ribbon carrier comprising a frame resting upon the platen and movable longitudinally therewith, means on said frame coacting with such machine to position said frame in place on said platen, ribbon holding means on said frame at each end thereof, said frame having a plurality of superposed ribbons mounted on said ribbon holding means and extending in front of said platen longitudinally thereof, a pair of superposed insertion guide members between adjacent ribbons and a pair of insertion guide members in front of the topmost ribbon, said guide members being mounted on said frame and positioned between said platen and said movable deflector plate, whereby an entry form may readily be inserted between said first pair of guide members to enter between said ribbons, and an entry form may readily be inserted between said second pair of guide members between the topmost ribbon and said deflector plate, and said entry forms may thereupon be moved longitudinally of said platen to clear said guide members, and positioned between and in front of said ribbons respectively without abutting against the upper edges thereof.

5. In a bookkeeping machine of the front feed type including a platen having a bail rod extending longitudinally thereof, and a movable deflector plate in front of said platen and extending thereunder longitudinally thereof; the combination therewith of a ribbon carrier, comprising a frame resting upon the platen and movable longitudinally therewith, means on said frame coacting with said bail rod to retain said frame in place on said platen, ribbon holding means on said frame at each end thereof, said frame having a plurality of superposed ribbons mounted on said ribbon holding means and extending in front of said platen longitudinally thereof, a plurality of insertion guides mounted on said frame associated with said ribbons, the insertion guides associated with all but the rear ribbon being reversely bent, closed at the top thereof and having a pair of guide members straddling the associated ribbon, an insertion guide between the adjacent guide member of the front ribbon and said movable deflector plate and an insertion guide between the guide member adjacent to the rear ribbon and said rear ribbon, whereby an entry form may readily be inserted between the insertion guide and guide member associated with the front ribbon and an entry form may readily be inserted between the insertion guide and guide member associated with the rear ribbon and said entry forms may thereupon be moved longitudinally of said platen to clear said guides and guide members, and positioned between and in front of said ribbons respectively without abutting against the upper edges thereof.

6. In a front feed machine of the type including a platen; the combination therewith of a ribbon carrier comprising a frame having side elements resting on said platen, means on each of said side elements coacting with the machine to retain said frame on said platen, releasable ribbon holding means on said side elements to which the ends of a plurality of superposed ribbons may be affixed respectively, such ribbons to extend in front of

said platen longitudinally thereof, and a plurality of associated insertion guides affixed to one of said side elements and associated with such ribbons when thus affixed, whereby an entry form may readily be inserted between such superposed ribbons.

7. In a bookkeeping machine of the front feed type including a platen and a movable deflector plate in front of said platen at the bottom thereof and extending longitudinally thereof; the combination therewith of a ribbon carrier, comprising a frame having side elements resting on said platen, means on each of said side elements co-acting with the machine to retain said frame on said platen and movable therewith, releasable ribbon holding means against said side elements to which the respective ends of a plurality of superposed ribbons may be affixed, such ribbons to extend in front of said platen longitudinally thereof, a pair of superposed insertion guide members between adjacent such ribbons and a pair of insertion guide members in front of the front ribbon, said guide members being affixed to one of said side elements, extending transversely of said platen in the front thereof and positioned between said platen and said movable deflector plate, the upper portion of each of said pairs of guide members being spaced, whereby an entry form may readily be inserted between the upper portions of each of said pairs of spaced guide members and thereupon moved longitudinally of said platen to clear said guide members, and positioned between and in front of such ribbons respectively without abutting against the upper edges thereof.

8. As an article of manufacture, a ribbon holder for a front feed machine, said holder comprising a generally U-shaped frame including a longitudinal bar and end arms extending angularly with respect thereto, means on said frame for releasable attachment thereof to said machine, ribbon holding means on each of said arms for releasable attachment of a plurality of ribbons to extend therebetween, and a plurality of associated insertion guides affixed to said frame to facilitate the positioning of forms between said ribbons.

9. The combination set forth in claim 8 in which each of said superposed insertion guides is a thin leaf of sheet metal and has a curved lower portion.

10. The combination set forth in claim 8 in which each of said insertion guides has an upper portion and a curved lower portion and the ends of said curved portions are stepped, with the end of the front guide extending beyond the end of the rear guide.

11. The combination set forth in claim 8 in which each of said insertion guides has an upper portion and a curved lower portion and the lower

portion of said front guide is of greater width than the lower portion of the guides therebelow and extends over the ribbon holding means at the end of the arm.

12. The combination set forth in claim 8 in which each of said insertion guides has an upper portion and a curved lower portion, with the upper portions of the guides being spaced from each other.

13. The combination set forth in claim 8 in which at least three insertion guides are provided, each of said guides having an upper portion and a curved lower portion, with the upper portion of the guides being spaced from each other,

14. The combination set forth in claim 8 in which each of said insertion guides has a laterally extending arm by means of which said guides are rigidly affixed to said associated end arm.

15. The combination set forth in claim 8 in which each of said insertion guides has an upper portion and a curved lower portion, with the upper portion of the guides being spaced from each other; and the ends of said curved portion are stepped, with the end of the front guide extending beyond the end of the rear guide, the lower portion of said front guide being greater in width than the lower portions of the guides below and extending over the ribbon holding means at the end of the arm.

16. The combination set forth in claim 15 in which at least three insertion guides are provided, with the guide between the topmost guide and the bottom guide having two separable plies.

17. The combination set forth in claim 8 in which each of said insertion guides has an upper portion and the ends of said upper portions are of graduated height, increasing toward the rear guide.

18. The combination set forth in claim 8 in which each of said insertion guides has an upper portion and the ends of said upper portions are of graduated height, increasing toward the rear guide and the lower ends of said guides being stepped, with the lower end of the front guide extending below the end of the rear guide.

JULIUS C. HOCHMAN.
